UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMPING DOOR FOR RAILWAY CARS AND THE LIKE.

Original application filed March 16, 1925, Serial No. 15,748. Divided and this application filed July 29, 1926. Serial No. 125,609.

My invention relates to improvements in dumping doors for railway cars and the like.

This application is a division of my pending application, Serial No. 15,748, filed March 16th, 1925.

An object of the invention is to provide a dumping door construction for railway cars and the like, in which the parts of each door are of metal, and arranged and braced in a novel manner, including elongated embossments in the unsupported portion of the door to reinforce the body thereof where the same is likely to sag under load, and including means for strengthening the free edge and corner portions of the door to render the construction of exceptional value when associated with door operating and supporting mechanism.

Another object of the invention is to so dispose the embossments in a floor door that the same will offer the minimum obstruction to shoveling should this be necessary at a time when it is not convenient to discharge the lading through the door openings.

It is a further object of the invention to so dispose the embossments as to offer the minimum obstruction to the free flow of material when the doors are in an inclined position and eliminate pockets or depressions within which moisture and water would accumulate and cause corrosion and damage.

It is also an object of the invention to reinforce the door by embossments of varying width whereby strength and resilience will be combined.

Other and further objects of the invention will more fully and clearly appear from the description and claims hereinafter following.

In the drawings forming a part of this specification, Fig. 1 represents a top plan view of a fragment of a railway car of the flat floor type, showing one of my improved dumping doors and the car construction associated therewith. Fig. 2 is a transverse sectional view through the car structure, illustrated in Fig. 1 and corresponding substantially to a line 2-2 of the same. Fig.

3 is a side elevational, partial sectional view, of the dump door and supporting means therefor, the side wall of the car being omitted to afford an unobstructed

view of the car door and its associated supporting means.

As shown in the drawings 10 represents a fragment of the center sill of a railway car of the flat floor type; 11 represents a fragment of the side sill of such car, only one side of the car being illustrated, and it will be understood that the center and side sills 10 and 11 extend longitudinally throughout the length of the car, and that construction similar to that illustrated in Fig. 1 forms the opposite side portion of the car. The center and side sills 10 and 11 are connected at intervals by means of cross-bearers 12 which are connected to the side and center sills in any suitable manner. Disposed between said crossbearers are dumping doors A which are shown herein as hinged to the center sill construction on suitable hinge brackets 13. Suitable door supporting and raising means are provided adjacent the swinging edges of the doors. Said means may consist of operating shafts 14 mounted in the ends of the cross-bearers 12 in suitable brackets 15. The brackets 15 in the form shown are provided with elongated slots 16 within which the shafts are adapted to have a movement of translation so as to be movable into supporting position beneath the doors from a position beyond the free edge thereof.

Each shaft 14 is provided at intervals with drums 17 on which are wound chains or flexible elements (not shown) whereby a connection is effected between the shaft and door to raise the latter. Formed integrally with each winding drum is a collar 18 having a series of serrations adapted to register with similar serrations on a bracket 38 mounted on the door structure.

Each of the doors A is of a novel construction comprising a metal plate of a size slightly greater than the dumping opening with which it is associated, said plate being provided along its forward and side edges with depending integral flanges 23, 24 and 25, and with a flange 26 which is inclined rearwardly and curved, so as to fit beneath the outstanding flange of the center sill.

Each of the doors A is swingably mounted upon the center sill 10 by means of hinge butts 13, preferably three in number, which are secured to the center sill by means of

rivets, and in spaced relation, two of the hinge butts 13 preferably being located adjacent the side edges of the door opening, and the remaining hinge butt 131 mounted 5 centrally between the two outer hinge butts. The hinge butts 13 and 131 are cut out to accommodate the curved flange 26 upon the door plate. The central hinge butt 131 is connected to the plate forming the door. A 10 by means of a hinge strap 29 riveted to the door and pivotally connected with the hinge butt by means of the pivot pin 30. The two outer hinge butts 13 are also provided with hinge straps 31 pivotally connected with the 15 associated hinge butts 13 by means of pivot pins 32. Door braces 33 are provided which are in the form of angle members, one flange of each of which is secured to the door plate by means of rivets, and the other flange of 20 which is disposed inwardly of the side edge of the door, and lies substantially perpendicular to the plane of the door plate. The door braces 33 extend transversely across the door plate to a point adjacent the outer free 25 edge thereof, the rear ends of the door braces being disposed in position to be secured to the hinge straps 31, rivets being provided which extend through the hinge straps 31, the horizontal flanges of the braces, and the 30 door plate.

Adjacent the forward edge of the door, and terminating a slight distance from the door braces 33 is a longitudinally extending brace in the form of a Z bar 34, one horizontal 35 flange 35 of which is riveted to the door plate, the other horizontal flange 36 being disposed somewhat below the plane of the door plate and the web of the Z bar being disposed perpendicularly to the plane of 40 the door plate.

Interposed between each end of the Z bar 34, and the adjacent vertical flange of a door brace 33 is an angular member 37, one flange of which lies between the end of the 45 Z bar 34 and the adjacent vertical flange of the brace, and the other flange of which is secured to the flange 36 of the Z bar 34 by means of rivets. Disposed on the outer side of each vertical flange of the related door 50 brace 33 is a casting 38 provided with serrations 39 on its under surface, the flange 23 of the door plate being recessed, as indicated at 40, to permit the projection therethrough of the outer end of the rack on the 55 casting. The side wall 41 of the casting, lying against the vertical flange of the adjacent brace 33, is fastened in position by means of rivets which extend through the wall 41, the vertical flange of the adjacent 60 door brace, and the vertically disposed flange of the supporting plate 37. The top wall 42 of the casting is secured to the door plate by means of rivets 43. Each casting 38 is reinforced by suitable ribs 44, and a 65 depending flange 45.

In order to strengthen the portion of the door plate lying between the braces 33, the metal is pressed upwardly to provide embossments 48, which are of elongated oval or elliptical form, the major axes of which 70 extend perpendicular to the pivotal axis of the door, the extremities of the embossments at their outer ends extending approximately to a point in line with the web of the Z-bar 75 34, and their rear ends extending to a point adjacent the rear edge of the door. The minor axes of such embossments are of such extent as to provide approximately equal spaces between the outer sides of the embossments and the braces 33, and between the inner 80 adjacent faces of the embossments, the embossments covering approximately two thirds of the area of the door between the braces 33. Each of the embossments 48 has a flat upper surface 49 of extended area 85 which is joined to the main body of the plate by inclined wall portions disposed as varying angles as indicated at 50 and 51, the inclined wall portions extending at such an angle that in shovelling the load, should it 90 be desired to do so, the shovel will slide easily over the sloping surfaces of the embossments, and also the greatest length and lesser slope is at the forward and rear ends of the embossments, as indicated at 50, in 95 the direction of flow of material, to provide for an unobstructed flow thereof when the doors are opened, and the steeper slope, as indicated at 51, divides the material to each side of the embossments thereby permitting 100 rapid discharge of the lading. The construction of the door can be somewhat varied if desired so that the center hinge strap 29 may be extended toward the Z-bar 34 a sufficient distance to provide a stiffener, in which 105 event the embossments 48 could be made smaller in size.

By this arrangement it will be apparent that the door is braced by a supporting framework consisting of the members 33, 110 and the Z-bar 34, and the rack members are securely connected by the plates 37 both to the braces 33 and the Z-bar 34, so that the rack members which support the door upon the shaft are supported by the framework, 115 and not by the metal of the plate itself. It also should be noted that the embossments brace the portion of the door which is most likely to sag under the weight of the load imposed thereon, the embossments being 120 formed with the portion of greatest width at substantially the line of greatest bending movement and the shape of the embossments, due to their gradually decreasing width as they approach the ends, ensures necessary 125 strength with resilience. Such embossments are arranged so that the portion of the door extending between the underlying reinforcements is braced in a simple and economical manner.

I have herein shown and described what I now consider the preferred manner of carrying out my invention, but the same is merely illustrative and I contemplate all changes and modifications that come within the scope of the claims appended hereto.

What I claim is:

1. In a railway car, the combination with means defining a dumping opening; of door braces extending transversely of said door; a Z bar having one flange connected to said door plate adjacent one longitudinal edge thereof, said Z bar having its ends spaced a small distance from said door braces; and bracing means having a portion connected to the other flange of said Z bar and to the respective door braces.
2. In a railway car, the combination with means defining a dumping opening; of a door for closing said opening comprising a metallic plate; transversely disposed angular door braces, each of which has one flange secured to said door plate, and the other flange extending perpendicularly to said door plate; a Z bar arranged adjacent one longitudinal edge of said door plate and having its ends spaced from the perpendicular flanges of said door braces; and means having a portion connected to the opposite flange of said Z bar, and to the perpendicular flanges of said door braces.
3. In a railway car, the combination with means defining a dumping opening; of a door for closing said opening comprising a metallic plate; transversely disposed door braces; a brace adjacent the longitudinal edge of said door, the ends of which are spaced from the inner sides of said door braces; rack members disposed on the outer sides of said door braces; and connecting means having portions secured to said longitudinal brace, and other portions connected to said transverse braces and said rack members.
4. In a railway car, the combination with means providing a dumping opening; of a door for closing said opening, comprising a metallic plate; transversely disposed door braces secured to said plate; a Z bar disposed adjacent to one longitudinal edge of said door and having one flange secured to said door plate, the ends of said Z bar being spaced from the inner sides of said transversely disposed door braces; rack members disposed on the outer sides of said door braces; and means connected to the other flange of said Z-bar and to said door braces, and said rack members.
5. In a railway car, the combination with means providing a dumping opening; of a door for closing said opening comprising a metal plate; of transversely disposed angular door braces, each of which has one flange secured to the door plate, and the other flange disposed perpendicularly to the plane

thereof; a Z bar disposed along the longitudinal edge of said door and having one flange connected with the door plate, the ends of said Z-bar being spaced from the perpendicular flanges of said door braces; rack members disposed on the outer sides of said door braces and secured to said door plate; and angular plates, each of which has one angular portion secured to the other flange of said Z-bar, and the other angular portion secured to the perpendicular flange of the adjacent door brace, and to said rack member.

6. In a railway car, the combination with means defining a dumping opening; of a door for closing said opening comprising a metallic plate; and means for bracing said door, said means including embossments formed in the plate, said embossments being oval in shape and disposed with their major axes extending in the line of flow of the dumping material when the door is opened; and a hinge member lying between a pair of embossments and secured to the door plate.

7. In a railway car, the combination with means defining a dumping opening; of a door for closing said opening comprising a metallic plate; bracing elements secured to the plate and extending in the direction of flow of the dumpable material when the door is opened; an embossment formed in the door plate and disposed intermediate the said bracing elements, said embossment presenting an extended flat surface raised outwardly from the main surface of the plate, the raised surfaces being connected with the plate by sloping wall portions of varying length, the connecting portions of greatest length being disposed in the direction of flow of the material.

8. As an article of manufacture, a hinged load sustaining door for dump cars and the like comprising: a main sheet metal plate; a series of hinges secured to the underside of the plate; and integrally formed indentations formed in said sheet metal plate, said indentations being disposed intermediate the hinges and formed with extended flat portions spaced away from the main door plate, said indentations decreasing in width near the ends thereof.

9. As an article of manufacture, a load sustaining door for dump cars and the like, comprising: a main sheet metal plate; and spaced integrally formed strengthening indentations in said sheet metal plate, said indentations having a substantially flat portion spaced away from the main plane of the door plate, said flat portion being connected to the main door plate by sloping wall portions extending at varying angles to the main portion of the sheet metal plate and so disposed that the connecting wall portions of least slope extend in the direction of flow of discharging material whereby said

material will flow over the said indentations when the door is in open position.

10. As an article of manufacture, a load sustaining door for dump cars and the like comprising: a main sheet metal plate; and integrally formed strengthening indentations in said sheet metal plate, said indentations having flat portions of extended width spaced away from the door plate and sloping wall portions connecting said flat portions with the main door plate, said sloping wall portions presenting a relatively flat slope in the direction of flow of the material and a relatively steeper slope at other locations.

11. As an article of manufacture, a hinged load sustaining door for dump cars and the like comprising: a main sheet metal plate; and spaced integrally formed strengthening indentations formed therein, each of said indentations including a flat section raised outwardly from the main body of the plate and sloping sections disposed at varying angles connecting said flat portion with the main body of the plate, said sloping sections of least slope being disposed in the direction of flow of material and those of relatively steeper slope being inclined transversely to the direction of flow of material whereby the section of least slope will direct material above the flat section of the indentations and the steeper slopes will divide the discharging material to either side of said indentations.

12. As an article of manufacture, a load sustaining door for dump cars and the like comprising: a main sheet metal plate; spaced integrally formed strengthening embossments in said plate, said embossments having flat portions of extended area raised above the door plate; and means for directing lading past said embossments when the door is open, said means including sloping

connecting wall sections between the raised portion of the embossment and the main door plate whereby a relatively flat slope is provided in the direction of flow of material to direct lading above the embossment and steep slopes to direct lading sidewise of the embossments.

13. As an article of manufacture, a load sustaining door for dump cars and the like comprising: a main sheet metal plate; a series of hinges secured to the door adjacent one edge thereof; a reinforcing framework secured to the underside of the door to strengthen the three remaining edges of the door; and integrally formed indentations formed in said sheet metal plate, to strengthen the door intermediate said hinges and framework, said indentations being formed with flat portions of extended width on substantially the line of maximum bending movement of the door and of gradually receding width towards the ends of said indentations.

14. As an article of manufacture, a load-sustaining and dumping door for dump cars and the like comprising: a main sheet metal plate having an integrally formed, strengthening embossment therein raised above the main plane of the plate, said embossment having an upper elongated flat portion united to the main portions of the plate by integrally sloping connecting portions, those connecting portions in the line of normal discharge of the load being of lesser slope than the remaining connecting portions, whereby to minimize impedance to the flow of material over said embossment when the load is being discharged.

In witness that I claim the foregoing I have hereunto subscribed my name this 27th day of July 1926.

ARGYLE CAMPBELL.
